BRACKET ASSEMBLY FOR SUPPORTING
YARN CARRIERS

Raymond J. Good, Philadelphia, Pa., assignor to
Fred C. Good & Sons, Inc., Philadelphia, Pa., a
corporation of Pennsylvania

Application April 7, 1953, Serial No. 347,203

5 Claims. (Cl. 66—126)

1

This invention relates to straight knitting machines and more particularly to supporting means for the yarn carriers of such machines.

It has been the practice in machines of this type to mount the yarn carriers directly on the carrier rods. This has been done by riveting the carriers directly to the rods, and also by drilling and tapping the carrier rods at the desired points. Where such machines are to be so arranged that different patterns may, from time to time, be knitted, it becomes a time consuming operation to move the yarn carriers upon the carrier rods or to remove them entirely therefrom.

Accordingly, it is a primary object of this invention to provide a bracket for removably and adjustably supporting the yarn carriers upon the carrier rods.

It is a further object of this invention to provide a bracket for the above purpose which can be quickly snapped on and off the carrier rod using only a screw driver or the like as a tool.

It is a further object of this invention to provide a two-piece carrier bracket mounting for the above purpose, which is easily and cheaply manufactured, and which will provide for readily removing and/or adjusting the position of the carrier on the carrier rods.

Other objects of the invention will be apparent from the following description read in conjunction with the attached sheet of drawing in which:

Figure 1 is a perspective view of a portion of a carrier rod with the bracket of the instant invention mounted thereon and supporting a yarn carrier;

Figure 2 is a side elevation of the bracket in partially assembled relation about a carrier rod;

Figure 3 is a plan view of the rear portion of the supporting bracket;

Figure 4 is a plan view of the front half of the bracket; and,

Figure 5 is a rear plan view of the member shown in Figure 3.

The rear portion of the bracket assembly comprises a member 10 substantially rectangular in outline, and having a recessed portion 11 forming a groove which extends completely across the member and at right angles to the sides thereof.

The dimensions of the recessed portion 11 are substantially those of the cross section of the carrier rod 12 so that the member 10 may fit over the carrier rod and slidably engage it. Immediately adjacent the recess 11 is a second recess 13 forming a slot parallel to recess 11 and being much shallower. The upper portion of the

2

member 10 is beveled from front to back to form a face, as indicated at 14, for a purpose which will hereinafter appear.

The front portion 15 of the bracket member is merely a flat, somewhat resilient plate having a pair of openings 16 and 17 adjacent the lower edge thereof for supporting the yarn carrier thereon, as shown in Figure 1. The upper edge 18 of member 15 comprises an outwardly rolled lip and includes an aperture 19, through which the yarn is threaded.

The two halves of the bracket assembly 10 and 15 may be conveniently assembled as shown in the drawing, by means of a pair of machine screws 20 and 21 threaded through openings in member 15 and engaging in tapped holes in member 10, which holes are located in the face of the second recess 13. Tightening of these screws will then cause sufficient friction between the bracket assembly and the carrier rod to hold it firmly in place at any selected point.

In order to apply the bracket assembly to the carrier rod, the front and rear portions may first be partially assembled as above, the front portion having the yarn carrier attached thereto, as shown in Figure 1. This assembly may then be sprung or snapped over the carrier rod because the beveled edge 14 will tend to force the upper portion of the member 15 outwardly as the assembly is pressed toward the carrier rod. Following this operation, the screws may then be tightened to hold the bracket assembly firmly in place.

From the foregoing, it will be apparent to those skilled in the art that the apparatus disclosed herein provides a new and very useful means for adjustably and removably supporting yarn carriers on the carrier rods of straight knitting machines. There will be many variations within the scope of the following claims.

40 I claim:

1. A bracket assembly for removably and adjustably supporting yarn carriers on the carrier rods of straight knitting machines comprising: a first plate-like element having a recessed portion 45 extending between a pair of opposed faces thereof of corresponding substantially to the width and thickness of a carrier rod; a second plate-like element adapted to overlie at least the recessed portion of said first element, the assembled pair 50 thus defining a passageway, the cross sectional dimensions of which correspond substantially to those of the carrier rods, said second element having openings adjacent one edge thereof for attaching a yarn carrier thereto; and means for removably securing said first and second ele-

ments in surrounding relationship to a selected part of a carrier rod.

2. A snap-on bracket assembly for removably and adjustably securing yarn carriers to the carrier rods of straight knitting machines, comprising: a rear element recessed to receive a carrier rod therein; a resilient plate-like front element adapted to overlie said rear element; and means for removably securing said elements in face to face relation so that they may be forced around a carrier rod, the recessed portion of said rear element receiving the rod, and the first mentioned means serving to hold the assembly firmly in place on the carrier rod.

3. A bracket assembly as defined by claim 2 in which the rear element includes a beveled face adjacent to and paralleling the recessed portion thereof for cooperation with the front element and carrier rod to effect a wedging action to spread the two elements as the assembly is forced over the carrier rod.

4. A bracket assembly as defined by claim 2 in which the rear element includes a beveled face adjacent and parallel to the recessed portion thereof and the front element includes an out-

wardly rolled lip along one edge thereof, said beveled face and outwardly rolled lip forming an inwardly tapered opening so that the assembly may readily be wedged over a carrier rod.

5. A bracket assembly for removably and adjustably supporting yarn carriers on the carrier rods of straight knitting machines comprising: a first plate-like element having a recessed portion in one face thereof corresponding substantially to the width and thickness of a carrier rod; a second plate-like element at least substantially coextensive with and adapted to overlie said first element; removable means for rigidly clamping a carrier rod between said elements, the rod occupying the recessed portion of the first element and being held therein by the second element; and means for attaching a yarn carrier to said assembly.
